Primary Examiner — Mark A Goodwin*(74) Attorney, Agent, or Firm* — Neal, Gerber & Eisenberg LLP**CLAIM**

The ornamental design for cab for a snow groomer, as shown and described.

DESCRIPTION

FIG. 1 is a front side perspective view of a cab for a snow groomer showing my new design.

FIG. 2 is a front view thereof.

FIG. 3 is a rear view thereof.

FIG. 4 is a side view thereof.

FIG. 5 is an opposite side view thereof.

FIG. 6 is a top view thereof; and,

FIG. 7 is a bottom view thereof.

The broken line showing of small surface features on the roof and the two elements on the rear of the cab in FIGS. 1-7 is included for the purpose of illustrating portions of the cab for a snow groomer and forms no part of the claimed design.
